UNITED STATES PATENT OFFICE.

REES C. MORGAN, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

DEVICE FOR PREVENTING RELATIVE ROTATION OF GUN CYLINDERS.

Application filed November 16, 1920. Serial No. 424,427.

To all whom it may concern:

Be it known that I, REES C. MORGAN, a citizen of the United States, and residing at Bethlehem, Northampton County, State of Pennsylvania, have invented certain new and useful Improvements in Devices for Preventing Relative Rotation of Gun Cylinders, of which the following is a specification.

In the manufacture of built-up guns, particularly in the manufacture of guns of large caliber by the shrinkage process, it has been found difficult to so construct and assemble the cylinders that the liner will not creep toward the muzzle end or rotate relatively to the tube or other cylinders, in service. The firing of the piece not only causes such a jar and concussion that the grip of the tube on the liner may be loosened, but the effect of the projectiles in passing through the bore is to cause the liner to rotate relatively to the tube, due to the tangential force exerted on the rifling by the projectile.

It is the object of the present invention to provide means whereby the tube and liner are prevented from rotating relatively to each other in service, and this object is attained by providing the tube and liner with spaced oppositely facing shoulders near the muzzle end and placing between these shoulders a device which engages each shoulder in such manner as to prevent relative rotational movement in the direction in which such movement would naturally be effected as a result of the direction of twist of the rifling, which may either be right hand or left hand.

One embodiment of the invention will be disclosed in the following description when taken with the accompanying drawing in which:

Figure 1 is a longitudinal section of a built-up gun showing the position of the locking device therein;

Figure 2 is a similar section taken at the muzzle end and to a larger scale, showing the improved locking means in position between the tube and liner;

Figure 3 is a section along the line 3—3 of Figure 2, this section being curved and following the contour of the outer surface of the liner;

Figure 4 is a side view of the specific form of locking device utilized.

While for the sake of convenience, the in-

vention is illustrated and described in connection with the tube and liner of a built-up gun, it will be understood that it may be utilized with any two adjacent cylinders of such a gun, or in fact to prevent relative rotation between any two concentric and close fitting cylinders.

The liner 10 is formed with a forwardly facing shoulder near its muzzle end and the tube 11 is formed with a reversely facing shoulder spaced a short distance in advance of the shoulder on the liner. These shoulders are preferably annular and at right angles to the axis of the gun. Between these shoulders is positioned a locking device, preferably in the form of a serrated or toothed ring 12 of steel harder than the steel of which the tube and liner are made and the teeth or serrations of the device are mashed into the opposed shoulders of tube and liner. The teeth or serrations are so formed that relative rotational movement of tube and liner in the direction of the arrows (Fig. 3) is strongly resisted.

In the embodiment illustrated the locking device is formed to oppose rotational movement of the cylinders of a gun having rifling of right hand twist but it will be obvious that it may be formed for use with a built-up gun having rifling of left hand twist.

The ring is placed in position as the gun is assembled. A method of assembly consists in placing the ring in position on the liner, which is disposed in a vertical position, and then lowering the heated tube over the liner and in finally exerting pressure in opposite directions on tube and liner so that the various cooperating shoulders of the tube and liner are firmly seated and the ring tightly jammed in position, its hardened teeth being mashed into the spaced reversely facing shoulders of tube and liner formed for this purpose.

The locking device may be made in various forms and applied to the gun in various positions and the invention is therefore not limited to the exact structure described and illustrated.

Having thus described my invention what I claim as new and desire to secure by Letters Patent is:

1. In a gun of the class described, the combination with two adjacent telescoped

cylinders, of an elongated element extending circumferentially of the gun between said cylinders and provided with means to grip both cylinders to hold them against relative movement of rotation.

2. In a gun of the class described, the combination with two adjacent telescoped cylinders, of a member curved to be concentric with the cylinders and fitting tightly therebetween, said member having means projecting therefrom to grip both cylinders and positively hold them against relative rotation.

3. In a gun of the class described, the combination with two adjacent telescoped cylinders, of an intermediate device for preventing relative rotation of said cylinders, said cylinders having reversely facing annular

shoulders and said device consisting in a serrated ring engaging said shoulders.

4. The combination with two telescoped cylinders of a built-up gun having annular reversely faced shoulders disposed transversely of the gun axis, of a toothed or serrated ring positioned between said shoulders with its teeth or serrations mashed into the shoulders, for the purpose set forth.

5. The combination with two telescoped cylinders of a built-up gun having annular reversely faced shoulders disposed transversely of the gun axis, of a hardened steel toothed or serrated ring positioned between said shoulders with its teeth mashed into the shoulders, for the purpose set forth.

In testimony whereof I affix my signature.

REES C. MORGAN.
